UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

SEWING MACHINE FOR FORMING CROSSED ZIGZAG STITCHES

Application filed June 26, 1929. Serial No. 373,759.

The invention relates to new and useful improvements in sewing machines and more particularly to a sewing machine for forming crossed zigzag stitches.

An object of the invention is to provide a machine of the above type wherein the needles are set abreast and are moved between consecutive stitch formations so as to exchange places with each other by the aid of swinging gates in which the needle bars carrying the respective needles are mounted.

A further object of the invention is to provide a machine of the above type wherein one of the needle bars is mounted on a swinging gate moving about a fixed axis while the other needle bar is mounted in an auxiliary swinging gate pivoted for oscillation in a direction substantially at right angles to the swinging movement of the first-named needle gate and also for bodily movement for carrying the needle from one extreme position laterally to the other extreme position.

A still further object of the invention is to provide a machine of the above type wherein the bodily shifted swinging gate is moved by a third swinging gate mounted to swing about the fixed axis on which the first swinging gate oscillates.

A still further object of the invention is to provide a machine of the above type wherein the swinging gate having a bodily movement is oscillated by toggle devices moving across a center line so that said gate is oscillated twice for each oscillation imparted to the other swinging gates.

These and other objects will in part be obvious and will in part be hereinafter more fully disclosed.

In the drawings which show by way of illustration one embodiment of the invention:

Fig. 1 is a front view of a sewing machine embodying the improvements.

Fig. 2 is a rear view of the same.

Fig. 3 is a view of the machine from the front end thereof.

Fig. 4 is a sectional view on the line 4—4 of Fig. 1.

Fig. 5 is a sectional view on the line 5—5 of Fig. 1.

Fig. 6 is a sectional view on the line 6—6 of Fig. 1 with the parts in the region of the work support omitted for the sake of clearness.

Fig. 7 is a detail in horizontal section showing the bodily shiftable swinging gate, the needle bar carried thereby and the means for operating said needle bar.

Fig. 8 is a view showing diagrammatically the position of the needles and the path of the needles as they change places with each other between consecutive stitches.

Fig. 9 is a similar view showing the path of movement of the needles as they change places between the next succeeding consecutive stitches.

Fig. 10 is a plan view on an enlarged scale showing diagrammatically the crossed zigzag stitches.

Fig. 11 is a detail partly in section and partly broken away showing the position of the cams when the swinging gates are at a dwell and the needle is reciprocating at one lateral extreme position.

Fig. 12 is a similar view showing the position of the cams when the needle gates are at their other extreme position.

The invention is directed to a sewing machine for forming crossed zigzag stitches. In Fig. 10 the stitch formed on the machine is indicated diagrammatically. In this view the fabric is indicated at 1 and the two needle threads are indicated at n and n'.

The direction of feed is indicated by the arrow. The needle carrying the needle thread n enters the fabric at a, while the needle carrying the needle thread n' enters the fabric at b.

The fabric is then fed for the next stitch formation and between these consecutive stitches the needles change places with each other, and the needle carrying the needle thread n enters the fabric at the point a', while the needle carrying the needle thread n' enters the fabric at b'.

The fabric is again moved another step and the needles enter the fabric at the points a'' and b'' respectively. After the next feeding movement the needles enter the fabric at the points a''' and b''' respectively, and so on.

It will thus be seen that there are two 100

lines of zigzag stitches formed in which the needles change places between consecutive stitches and cross the zigzag stitches.

- The needle carrying the needle thread *n*
 5 is indicated at 2 in the drawings, while the
 needle carrying the needle thread *n'* is indi-
 cated at 3 in the drawings. As clearly
 shown in Fig. 8, the needle 2 moves in the
 direction of the arrow *c* from one extreme
 10 lateral position to the other extreme lateral
 position. The needle 3 moves in the path
 indicated by the arrow *d* from the left hand
 lateral extreme position to the right hand
 lateral extreme position. Between the next
 15 stitch formations the needle 2 again moves
 in the path indicated by the arrow *c* which
 is straight across or substantially so to the
 other extreme side of the seam, while the
 needle 3 moves forwardly and laterally in
 20 the path indicated by the arrow *d* to the
 other extreme of its lateral movement. In
 order to accomplish this movement of the
 needles, the needle bar carrying the needle
 25 2 is mounted in a swinging gate pivoted to
 swing about a fixed vertical axis at the rear
 side of the needle head. This gate is oscil-
 lated so as to move the reciprocating position
 of the needle bar from one lateral ex-
 30 treme position to the other lateral extreme
 position. The needle bar carrying the
 needle 3 is mounted in an oscillating gate
 which moves the needle bar in a direction
 substantially at right angles to the path of
 35 lateral movement of the needle 2. This
 swinging gate carrying the needle 3 is in
 turn pivoted on a swinging gate which
 moves in a manner similar to the swinging
 gate carrying the needle 2 and about the
 40 same vertical axis.
 By this arrangement the needle bars are
 caused to shift so that the needles will
 change places with each other; the needle 2
 moving directly across from one position to
 45 the other, while the needle 3 moves out
 around the needle 2 to its other lateral ex-
 treme of movement.

Referring more in detail to the drawings
 which show one embodiment of the invention,
 the machine includes a supporting bed
 50 4 carrying a work support 5. A standard
 6 is mounted on the supporting bed and is
 provided with an overhanging arm 7 at the
 outer end of which is the needle head 8.
 The needle 3 is carried by a needle bar 9
 55 and the needle bar 9 is mounted for reciprocation
 in a swinging gate 10. This swinging gate 10 is in turn pivoted to swing about a vertical axis 11 at the free end of a swinging gate 12 (see Fig. 6). The swinging gate
 60 12 is mounted to swing about a vertical axis 13 at the rear of the needle head. Said swinging gate 12 is mounted for free swing-
 ing movement on a rod 14. At the lower
 end of the needle bar 9 is a collar 15 carry-
 ing a laterally projecting arm 16. The

needle 3 has its shank 17 bent at right angles to the length of the needle and this shank is mounted in the laterally projecting arm 16.

The needle 2 is carried by a needle bar 70
 18. This needle bar 18 is mounted for re-
 ciprocation in a swinging gate 19. The
 swinging gate 19 is mounted for free move-
 ment on this same rod 14 at the rear of the
 75 needle head.

The material is held on the work support
 by a presser foot 20 carried by a presser bar
 21. Projecting laterally from the presser
 bar 21 is a forked arm 22. The lower end
 80 of the rod 14 is cut away at its sides so as to
 provide parallel faces and this portion of
 the rod lies in the forked end of the arm 22.
 This serves as a means for preventing the
 rod 14 from oscillation.

The needle bar 18 is reciprocated by a 85
 needle lever 23 which is pivoted at 24 to the
 standard 6. Said needle lever is connected
 by a link 25 to a lug 26 carried by the needle
 bar 18 (see Fig. 6). The lug 26 is mounted
 on a sleeve 27 which is fixed to the needle
 90 bar. Thus it is that the needle bar 18 is
 reciprocated in its swinging gate. This
 link connection between the needle lever and
 the needle bar is substantially vertical and
 will permit the oscillations of the gate and
 95 the shifting of the needle bar from one
 lateral position to the other.

Projecting from the sleeve 27 is a lug 29.
 Mounted on the needle bar 9 is a sleeve 30.
 This sleeve has a rearwardly projecting arm
 100 31 provided with spaced members which re-
 ceive therebetween the lug 29. The arm 31
 is provided with a vertical recessed portion
 32 which engages a projecting plate 33 on
 the swinging gate 10. This prevents the
 105 needle bar 9 from oscillating about its axis.
 The arm 31 can slide up and down on the
 plate 33. The plate 33 is a part of the swing-
 ing gate 10.

The needle bar reciprocates in the sleeves
 110 34, 34 which are also carried by the swinging
 gate 10. These sleeves in their fixed relation
 to the swinging gate 10 hold the needle bar
 in a fixed lateral position on said swinging
 gate 10 while the connection between the
 115 sleeve 30 on the needle bar 9 and the project-
 ing lug 29 causes the needle bar to recipro-
 cate vertically in the sleeves 34, 34. It is
 through this structure that both needle bars
 are simultaneously reciprocated by the nee-
 120 dle lever 23. The needle lever 23 is oscillated
 by an eccentric strap 35 cooperating with an
 eccentric on the main shaft 36. The swing-
 ing gate 12 on which the swinging gate 10 is
 mounted for bodily movement is oscillated
 125 by means of an arm 37 carried by a sleeve
 38 which is fixed to a shaft 39. This shaft is
 mounted in bearings 40 and 41 carried re-
 spectively by the standard and overhanging
 arm. A link 42 is connected to a ball stud
 130

43 attached to the lower end of the arm 37 and also to a ball stud 44 attached to the swinging gate 12.

The gate 10 is mounted on a rod 45 which forms the axis 11 on which said gate oscillates. The rod 45 is at the outer or free end of the gate 12 which swings about the axis 13. When the shaft 39 is oscillated it will through the link 42 swing the gate 12 about the axis 13. This causes the axis 11 at the free end of the gate 12 to swing in a circle about the axis 13 as a center.

The needle bar 18 is mounted for reciprocation in the swinging gate 19, as above noted. This gate oscillates about the axis 13 which is the same axis on which the swinging gate 12 oscillates. Fixed to this swinging gate 19 is a laterally projecting arm 46. This laterally projecting arm 46 carries a ball stud 47. A link 48 connected to said ball stud is in turn connected to a ball stud at the lower end of an arm 49 which is formed integral with a collar 50 and the collar 50 is clamped to the shaft 39.

As the shaft 39 oscillates it will swing the arm 46 which in turn will swing the gate 19. It will be noted that the arm 46 projects from the opposite side of the axis of support for the gate 19 from the mounting of the needle bar therein while the connection between the arm 37 and the swinging gate 12 is at the same side of the axis as the mounting for the swinging gate 10 which carries the needle bar 9. As a result, when the shaft 39 oscillates, it will move the swinging gate 12 in one direction and the swinging gate 19 in the opposite direction on the pivotal axis 13.

The shaft 39 is oscillated by means of an arm 51. Said arm carries a ball stud 52 to which a link 53 is attached. This link 53 at its other end is connected to a ball stud 54 which is mounted for adjustment in a swinging segment 55. This swinging segment has a slot 56 therein along which the ball stud 54 is adjustable. The swinging segment 55 is mounted on a shaft 57. This swinging segment is provided with a fork 58 which engages a cam 59 secured to the face of a gear 61. The gear 61 is in turn mounted on a suitable stub shaft journalled in a bearing in the standard 6. This gear 61 meshes with a gear 62 on the main shaft 36. The gear 61 is of such dimensions as to rotate once for each two rotations of the gear 62. Thus it is that the shaft 39 is given movement in one direction for each complete reciprocation of the needle bars, after which it is moved in the other direction and the needle bars are again reciprocated.

The cam 59 is shaped so as to give a dwell to the oscillations in the shaft 39 so that the swinging gates are oscillated and then come to a dwell while holding the needle bar in

a fixed position while it is reciprocating for puncturing the fabric and forming the stitch. After the needles are well above the fabric, then the swinging gates are moved for the positioning of the needle bars for the next stitch formation.

The swinging gate 10 is oscillated on its support by a sleeve 63. This sleeve is mounted for free movement on the shaft 39. Fixed to the sleeve is an arm 64. A link 65 is connected to a ball stud 66 at the lower end of the arm 64. This link is connected at its other end to a ball stud 67 at the lower end of an arm 68 carried by a sleeve 69 fixed to a rock shaft 70. This rock shaft 70 is mounted for oscillation in a bearing 71 which is fixed to the needle head and overhanging arm 7 by suitable screws 72, 73. Depending from the other end of the rock shaft 70 is an arm 73 carrying a sleeve 74.

Mounted on the needle bar 9 is a yoke 75. The yoke 75 straddles the lower sleeve 34 of the gate 10. Projecting from this yoke 75 is a rod 76, which loosely engages the sleeve 74. As the arm 64 is oscillated, the rock shaft 70 will impart oscillations to the sleeve 74 in a direction toward and from the needle head. This back and forth movement of the sleeve 74 will swing the gate 10 on its axis 11. This moves the needle bar 9 in a direction toward and from the needle head and in a path which is substantially at right angles to the path of movement of the needle bar 18 as the gate 19 moves it from one lateral extreme position to the other.

The sleeve 63 on the shaft 39 is given a complete oscillation for each single oscillation of the shaft 39. When the shaft 39 moves in one direction the gates 12 and 19 are swung on the pivotal axis 13. As noted above, the shaft 39 is moved in one direction and then given a dwell. During this swinging movement of the gate which moves the needle bar 18 from one lateral extreme position to the other lateral extreme, the gate 10 is swung away from the needle head and at the same time the gate 12 in which it is mounted moves so as to shift the gate 10 bodily.

The gate 10 is moved back again toward the needle head while the gate 12 is making its lateral movement. As a result the needle 3 carried by the needle bar 9 takes the curved path of travel practically moving around the needle 2 as shown in Figs. 8 and 9.

The sleeve 63 receives its oscillations from an arm 77. This arm 77 is fixed to the sleeve 63 and carries a pivot pin 78 to which a link 79 is attached. The link 79 at its other end is pivoted to a pivot pin 80 carried by a lever 81. The lever 81 is pivoted at 82a to a bracket 83 carried by the bed 4. The lever is provided with spaced plates which cooperate with a cam 82 mounted on

the stub shaft carrying the cam 59. The cam 82 is so shaped as to oscillate the lever to the left and to the right of the position shown in Fig. 5. It is also so shaped that 5 when the lever is swung to its extreme at the right it will remain at a dwell at this point and when it is swung to the extreme movement to the left, it likewise remains at a dwell. The lever and the link 79 per- 10 form a toggle action which gives to the sleeve 63 two oscillations with a dwell at each end of the oscillations during one os- cillation of the shaft 39 and both the sleeve and the shaft receive their oscillations from 15 the one stub shaft which is driven at one- half the speed of the main shaft.

These movements are so combined that the following operation takes place: The needle 2 carried by the needle bar 18 enters 20 the fabric at one lateral extreme position, while the needle 3 carried by the needle bar 9 enters the fabric at the other lateral ex- treme position. The needles are moved into and out of the fabric by the same needle bar 25 reciprocating means. After the needles are withdrawn from the fabric, then it is that the swinging gates are operated. This oc- curs while the needles are above the fabric and the swinging gates mounted to move 30 about the axis 13 are given a movement in one direction for each complete reciproca- tion of the needle bars. This positions the needle bars at their extreme lateral move- ments and maintains them at this position 35 while a stitch is being formed. The needle gate carrying the needle 2 moves the needle bar directly across from one lateral extreme position to the other, said needle bar mov- ing in a curved path about the axis 13 as 40 a center. The other needle bar 9, however, carrying the needle 3, will be moved forward as it moves laterally due to the swinging of the gate 10 by this toggle actuating mech- anism. It not only moves forward as the 45 gate swings, but also rearwardly, moving out and back, completing an oscillation for each oscillation of the main swinging gate 12 on which it is mounted. This causes the needle to move in the curved path indicated 50 in Figs. 8 and 9.

Thus it is that by swinging gates the needles are caused to change places between consecutive stitches. From the above it will be apparent that the needle bars are moved 55 laterally and caused to change places with each other through a means whereby the lateral movements imparted to the bars may be simultaneously adjusted, as the swinging gates which move the needle bars laterally 60 are both operated from the same shaft, and the extent of oscillation given the shaft may be varied. This insures that the lateral shift given the needle bars when varied shall be symmetrically disposed relative to the 65 line of feed.

Cooperating with the needles beneath the work support is a thread carrying looper 84. This looper cooperates with both needles for the reason that when the needles enter the fabric they enter the fabric abreast. A loop retainer 85 cooperates in holding the loops well back on the looper so that both needles will enter the looper thread triangle. 70

This looper mechanism is of the usual 75 construction and detailed description thereof is not thought necessary.

The material is fed across the work sup- port by a feed dog 86 which cooperates with the presser foot 20. This feed dog is a part 80 of the ordinary four-motion feeding mech- anism and detailed description thereof is not thought necessary.

From the above it will be apparent that I 85 have provided a sewing machine for forming crossed zigzag stitches wherein the needle bars are positively reciprocated and posi- tively shifted by swinging gates so that the needles are caused to change places with each other between consecutive stitches. It 90 is obvious that the crossed zigzag stitches formed on this machine may be applied in any desired way to a fabric either at the edge of the fabric or within the limits of 95 the fabric.

It is also obvious that minor changes in the details of construction and the arrange- ment of the parts may be made without de- parting from the spirit of the invention as set forth in the appended claims. 100

Having fully described my invention, what I claim as new and desire to secure by Letters Patent, is:—

1. A sewing machine including a work 105 support, a feeding mechanism, needles ar- ranged abreast, a needle bar for each needle, swinging gates for supporting said needle bars, and means for operating said gates whereby said needles are caused to move lat- erally and change places with each other be- 110 tween stitches and crossed zigzag stitches formed, said means including devices where- by the lateral movements imparted to the needle bars may be simultaneously varied. 115

2. A sewing machine including a work 120 support, a feeding mechanism, needles ar- ranged abreast, a needle bar for each needle, a swinging gate for one of said needle bars pivoted in rear of the stitching point for moving the needle bar laterally of the line 125 of feed, a swinging gate for the other needle bar pivoted at one side of the line of feed for moving the needle bar back and forth in the line of feed, and means for moving said last-named swinging gate bodily laterally whereby said needles are caused to change places with each other between stitches and crossed zigzag stitches formed. 130

3. A sewing machine including a work 135 support, a feeding mechanism, needles ar-

- ranged abreast, a needle bar for each needle, a swinging gate for one of said needle bars pivoted in rear of the stitching point for moving the needle bar laterally of the line of feed, a swinging gate for the other needle bar pivoted at one side of the line of feed for moving the needle bar back and forth in the line of feed, a third swinging gate on which said second swinging gate is pivotally mounted, and means for oscillating said third swinging gate for moving the second swinging gate bodily laterally whereby said needles are caused to change places with each other between stitches and crossed zig-zag stitches formed.
4. A sewing machine including a work support, a feeding mechanism, needles arranged abreast, a needle bar for each needle, a swinging gate for one of said needle bars pivoted in rear of the stitching point for moving the needle bar laterally of the line of feed, a swinging gate for the other needle bar pivoted at one side of the line of feed for moving the needle bar back and forth in the line of feed, a third swinging gate on which said second swinging gate is pivotally mounted, means for oscillating said third swinging gate for moving the second swinging gate bodily laterally whereby said needles are caused to change places with each other between stitches and crossed zig-zag stitches formed, means for oscillating said first and last-named swinging gates in unison but in opposite directions, said means for oscillating said second swinging gate including devices for giving to said gate a back and forth movement, while the other swinging gates are moving in one direction.
5. A sewing machine including a work support, a feeding mechanism, needles arranged abreast, a needle bar for each needle, a swinging gate for one of said needle bars pivoted in rear of the stitching point for moving the needle bar laterally of the line of feed, a swinging gate for the other needle bar pivoted at one side of the line of feed for moving the needle bar back and forth in the line of feed, a third swinging gate on which said second swinging gate is pivotally mounted, means for oscillating said third swinging gate for moving the second swinging gate bodily laterally whereby said needles are caused to change places with each other between stitches and crossed zig-zag stitches formed, means for oscillating said first and last-named swinging gates in unison but in opposite directions, said means for oscillating said second swinging gate including an oscillating lever and a link movable into alignment and to a position at each side of said alignment for imparting a back and forth movement to the second swinging gate, while the other swinging gates are moving in one direction.
6. A sewing machine including a work support, a feeding mechanism, a needle, a needle bar carrying said needle, a swinging gate in which said needle bar is mounted for reciprocation, a second swinging gate pivoted in rear of the needle and on which said first-named swinging gate is pivotally mounted, means for oscillating said second-named swinging gate, and means for oscillating the first-named swinging gate on said second swinging gate, said last-named means including a lever and a link movable into alignment and to each side of alignment whereby said first swinging gate is moved back and forth, while the other swinging gate is moved in one direction.
7. A sewing machine including a work support, a feeding mechanism, a needle, a needle bar carrying said needle, a swinging gate in which said needle bar is mounted for reciprocation, a second swinging gate pivoted in rear of the needle and on which said first-named swinging gate is pivotally mounted, means for oscillating said second-named swinging gate, and means for oscillating the first-named swinging gate on said second swinging gate, said last-named means including a shaft, a swinging lever, a cam on said shaft for swinging said lever and giving an extended dwell thereto at each end of its oscillation, a rock shaft connected to said first-named swinging gate, an arm carried by the rock shaft, a link connecting said arm to said lever, said link and lever being disposed so as to move into alignment and to each side of alignment whereby said rock shaft is given two complete oscillations for each oscillation of the lever, a rock shaft connected to said second-named swinging gate for oscillating the same, and means operated by said shaft for oscillating said second-named rock shaft once for each oscillation of the lever and for giving a dwell to said rock shaft at each end of its oscillation whereby said needle bar may be moved laterally and given a dwell while the needle is caused to penetrate the fabric for the stitch formation.
8. A sewing machine including in combination a work support, a feeding mechanism, a needle, a needle bar carrying said needle, a swinging gate in which said needle bar is mounted, and means for swinging said gate so as to move the needle back and forth in the line of feed, said means including a rock shaft, an arm carried by the rock shaft, a sleeve mounted on said arm, a rod attached to the swinging gate and freely movable in said sleeve, and means for moving said swinging gate bodily laterally of the line of feed.
9. A sewing machine including in combination a work support, a feeding mechanism, a needle, a needle bar carrying said needle, a swinging gate in which said needle bar is mounted, and means for swinging

said gate so as to move the needle back and forth in the line of feed, said means including a rock shaft, an arm carried by the rock shaft, a sleeve mounted on said arm, a rod attached to the swinging gate and freely movable in said sleeve, means for oscillating said rock shaft and giving an extended dwell thereto at each end of its oscillation, and means for moving said swinging gate bodily laterally of the line of feed and giving a dwell thereto at each end of its movement whereby the needle bar may be set at different positions relative to the fabric and maintained in said set position while the needle enters the fabric for the switch formation.

In testimony whereof, I affix my signature.

JOSEPH BERGER.
